CLAIM

The ornamental design for an exercise strap, as shown and described.

DESCRIPTION

FIG. 1 is a perspective view of the exercise strap showing my new design;

FIG. 2 is an enlarged perspective view thereof;

FIG. 3 is a front elevational view of a portion thereof, the rear elevational view of the portion being a mirror image;

FIG. 4 is a top plan view of the portion shown in FIG. 3; and,

FIG. 5 is a bottom plan view of the portion shown in FIG. 3. Any broken line illustration of environmental structure in the drawings is not part of the design sought to be patented.
